CYLINDER LOCK

Alexander Suter, Basel, Switzerland, assignor to
 "Spiku"-Trust, Vaduz, Liechtenstein, a corporation of Liechtenstein

Application March 28, 1944, Serial No. 528,377
 In Switzerland January 30, 1943

4 Claims. (Cl. 70—385)

The present invention refers to changeable combination cylinder locks and keys therefor.

In such locks the key can be introduced into the lock, or withdrawn from the lock, in three positions, namely the locked position, the open position and the intermediate position (neutral position). In neutral position, the tumblers of the lock may be set to a new combination by the insertion of a key with a different combination of the pegs of the key-bit. Thereafter the lock 10 will react to this new key and it will no longer be possible to operate it by means of the original key.

Such locks are conveniently provided with one master key and a certain number of standard keys in which the pegs are not adjustable, for which, however, the required number of pegs in various lengths is available for fitting to these keys. In other words, the standard keys can be fitted with the required pegs in a combination corresponding to that of the master key. The master key is equipped with bit pegs provided with a scale, so that the pegs may be set according to any pre-selected figure, for instance six key pegs set to a six figure number. It will be advisable to keep the master key under lock and key and to use for locking and unlocking a certain number of standard keys set in accordance with the master key. Of course, the consequence of any modification of the master key is to render necessary the re-setting of all the standard keys; it follows as a matter of course that the setting of the master key should be modified as seldom as possible and only in case of need.

The present invention aims at such a design of the lock and of the corresponding keys as shall insure that, in neutral lock position, it shall be impossible to withdraw the standard key from, or re-insert it into, the lock and that even for the master key this shall be possible under certain conditions only.

The invention is characterised by the feature that at least one locking organ—which can be released or disconnected—is provided for preventing the unintentional withdrawal of the keys out of the neutral lock position, and that the bit of the master key, as compared with the bit of the standard key, has a different cross section owing to which—with the locking organ released or disconnected—the master key only, to the exclusion of the standard keys, may be withdrawn from, or inserted into, the lock when in neutral position.

The attached drawing shows a preferred embodiment of the present invention.

Figure 1 is a section along the line 1—1 of Figure 2, showing the lock in neutral position.

Figure 2 is a longitudinal section along the broken line 2—2 of Figure 1.

Figure 3 shows the grouping of the key locking organs, the lock being in open position.

Figure 4 is a fragmentary detail of Figure 3.

Figure 5 is a front elevation of the lock in locked position.

Figure 6 is the key slot in neutral position.

Figure 7 is the same, with the locking organ released.

Figures 8 and 9 are end and side elevations respectively of the bit of the master key.

Figures 10 and 11 are end and side elevations respectively of the bit of the standard key.

The housing 1 is provided with six dovetail-shaped grooves 2 in which the serrated dovetails 3 are axially slidable. In the housing 1 is lodged a cylinder 4 provided with six dovetail-shaped grooves 5 also extending axially. To each of these grooves 5 corresponds a hole 6 and a slot 7. T-shaped slides are housed in the grooves 5; they are constituted by the dovetail-shaped piece 8,

25 the connection 9 and the bolt 10. The springs 11 inserted in the holes 6 maintain the slides in the neutral position shown in Fig. 2. The slides, in their part 8, are provided with noses 12 reaching over the ends of the dovetails 3.

When inserting the key into the slot 13 the bit pegs 14 displace the slides rearwardly, each slide according to the setting of the respective peg. Through the subsequent turning of the key, and thus of the cylinder 4, the serrations 15 of the cylinder 4 engage the serrations of the dovetails 3, so that these latter are locked axially in their shifted position. The noses 12 of the slides are simultaneously disengaged from the dovetails 3, so that the slides are forced back into their initial position

30 40 by the pressure of the springs 11, locking the lock. The cylinder can only be turned back by a key provided with a bit exhibiting the same peg combination as the key by which the slides were displaced, so that these are forced back into the exactly identical spot as previously, and through rotation the dovetails 3 again reach a position between the noses 12 of the slides. In order to unlock the lock the key shall be inserted and then given a 60° turn to the left, so that the dovetails 3 now catch into the adjacent serrations 15' which lock the dovetails 3 in the open position.

35 45 50 55 Between these two cylinder positions there is an intermediate position as shown in Figs. 1 and 2, the "neutral position," in which the grooved bodies 3 are resting between the noses

12 of the slides. While in neutral position, the lock can be set to another combination of the pegs. It follows that, should the key be removed from the lock in this position and another key with other peg combinations inserted, the lock will set itself automatically to this new key, with the result that the previous key will not fit any more. Should therefore a key be unintentionally withdrawn while the lock is in neutral position, the lock could be opened and locked by any other key and the possessor of the first key would be unable to open his lock an more.

In order to eliminate this danger, the keys—as shown in Figs. 8-11—are provided with grooves 16 accommodating locking organs 17, 18. Of these locking organs the lock plates 17 are fixed to the housing 1 by the pins 19 and extend into the groove 20 of the cylinder 4. These lock plates are provided with recesses 21 which in the open lock position corresponds to the key slot 13. The locking discs 18 of the locking organs are rotatably mounted in the groove 20 of the cylinder 4. These are pressed by the noses 23 of the cover disc 24, by means of the spring 25, against the locking plates 17 (see Figs. 3 and 4). The locking discs 18 are provided with recesses 26 which enable the key to be withdrawn from the lock in locked position. The bars 22 and 22' of the cover disc 24 are carried through slots 27 of the housing 1, and the cover disc 24 is rotatably positioned on the housing 1 by means of the snap ring 28. The bar 22' is provided with a perforation P into which one end of the spring 25 is hooked. The other end of the spring 25 is hooked in the bolt 29 fixed on the housing 1. (See Figs. 2 and 3.) The cover disc 24 is provided with flutes 30, so that it can be turned by hand against the spring pull. The lock plates 17 are provided with recesses 31 defining corners 33 corresponding to the recesses 32 of the master key, Figs. 8 and 9. Fig. 6 shows the key slot 13 in neutral position. The corners 33 of the locking plate 17 and the corners 34 of the locking discs 18 occupy the extreme ends of the key slot 13 and engage the grooves 16 of the key, with the result that, although the key may be turned it cannot be withdrawn from the lock in this position. If it is desired to change the lock to another combination of the bit pegs, the master key (Figs. 8 and 9) is inserted into the lock and turned until the neutral position is reached.

By turning the cover disc 24 the locking discs 18 are shifted so that their corners 34 move out of the range of the key slot 13. The master key can now be withdrawn and altered at will because of its recess 32 corresponding to the corner 33 which permanently occupies the position shown in Figures 6 and 7. The lock remains in neutral position until the modified master key is again inserted into the lock. In order to make it impossible that in the interval another key besides the master key shall be inserted into the lock, the recess 32 of the master key is not to be found in the standard keys. There is thus no possibility whatsoever to insert a standard key into the lock in neutral position, or to withdraw it. Thus there is an absolute guarantee that the lock cannot be tampered with by third parties, whether by mistake or intentionally. According to the nature of the invention, the locking of the key-hole in

neutral position may also be secured by means other than those described without departing from the idea underlying the invention.

It is apparent that the specific illustrations shown above have been given by way of illustration only and not by way of limitation, and that the structures above described are subject to wide variation and modification without departing from the scope or intent of the invention, all of which variations and modifications are to be included within the scope of the present invention.

I claim:

1. A changeable combination cylinder lock comprising, in combination with a housing, a cylinder rotatable in said housing between a locked, an unlocked and a neutral position, said cylinder being formed with a key slot, and a master key and standard keys adapted to operate said lock, said standard keys having a cross section adapted to occupy substantially all of said key slot, a circumferential groove formed in said cylinder, a recess formed in said keys axially coincident with said groove, a locking plate fixedly mounted in said housing and having a portion extending into portions of said groove and said recess and occupying a part of said key slot in the neutral position of said cylinder, and a recess formed in said master key corresponding to said slot-occupying portion.

2. In a lock according to claim 1, a locking disc rotatably mounted in said groove and having a portion adapted by rotation of said disc to occupy and to move out of another part of said key slot in the neutral position of said cylinder.

3. In a lock according to claim 1, a locking disc rotatably mounted in said groove and having a portion adapted by rotation of said disc to occupy and to move out of another part of said key slot in the neutral position of said cylinder, a spring actuating said disc into occupying position and external means for rotating said disc out of said position.

4. A changeable combination cylinder lock comprising, in combination with a housing, a cylinder rotatable in said housing between a locked, an unlocked and a neutral position, said cylinder being formed with a key slot, and a master key and standard keys adapted to operate said lock, said standard keys having a cross section adapted to occupy substantially all of said key slot, a circumferential groove formed in said cylinder, a recess formed in said keys axially coincident with said groove, a locking plate fixedly mounted in said housing and having a portion extending into portions of said groove and said recess and occupying a part of said key slot in the neutral position of said cylinder, a recess formed in said master key corresponding to said slot-occupying portion, a locking disc rotatably mounted in said groove and having a portion adapted by rotation of said disc to occupy and to move out of another part of said slot in the neutral position of said cylinder, a spring actuating said disc into occupying position and a cover disc rotatably mounted on said housing and adapted to rotate said disc out of said slot occupying position.

ALEXANDER SUTER.
